Patented May 30, 1922.

UNITED STATES PATENT OFFICE.

JAMES J. MOUNT, OF CHICAGO, ILLINOIS.

DENTAL FLASK.

1,417,938.

Specification of Letters Patent. Patented May 30, 1922.

Application filed September 29, 1921. Serial No. 504,171.

To all whom it may concern:

Be it known that I, JAMES J. MOUNT, a citizen of the United States of America, and a resident of Chicago, county of Cook, and 5 State of Illinois, have invented a new and useful Improvement in Dental Flasks, of which the following is a specification.

This invention relates to centrifugal casting machines designed for casting dental 10 inlays and the like.

The main objects of this invention are to provide a centrifugal casting machine having an improved form of flask, in which the crucible and matrix may be simultaneously formed in a single mold; to provide improved means for molding the crucible and matrix; to provide an improved arrangement of the flask with respect to the rotatable supporting member; and to provide 15 improved mechanism for imparting a uniform rotation to the supporting member and flask.

An illustrative embodiment of this invention is shown in the accompanying drawings, in which—

Figure 1 is a side elevation of the apparatus, showing the upright support in vertical section.

Figure 2 is a side elevation of the apparatus taken from the right of Figure 1.

Figure 3 is a vertical section of the flask.

Figure 4 is a transverse section of the flask taken on the line 4—4 of Figure 3.

In centrifugal casting machines which are now in common use, the mold in which the matrix is formed is detachable from the crucible. The crucible is made of suitable refractory material and is used for an indefinite number of operations, while the 35 matrix mold is necessarily changed for each casting. When the same crucible is used repeatedly it becomes coated with slag and other foreign substances which mix with the molten metal flowing into the matrix to form an imperfect casting. Also, the repeated heating of the same crucible produces a rough surface within the crucible which greatly retards the flow of the molten metal.

The present invention involves the use of 50 a flask in which the crucible and matrix are simultaneously formed in a single mold and a new mold is made for each casting. The flask is carried by a rotatable supporting arm which is rotated by an improved form of

driving mechanism constructed to operate 55 uniformly for each casting operation.

In the form shown, the apparatus comprises an upright support 1, on which is mounted an improved form of driving mechanism 2, for rotating a supporting member 3, pivotally mounted on a horizontal axis 60 and carrying an improved form of flask 4, in which the casting operation is performed by the resultant action of inertia and centrifugal force.

The upright support comprises a tubular standard 5 having a threaded cap 6 at its upper end and a base member 7 which may be bolted or otherwise secured to a table or other support. Mounted on the upright support is a laterally extending bracket 8, having a clamping part 9 which embraces the tubular standard. Journaled in the bracket, 65 is a horizontally disposed shaft 10 having fixed on its outer end the rotatable member 3. 70

Loosely supported on the inner end of the shaft 10 is a gear 11, which projects through an opening 12 in the standard 5 for engagement with the driving mechanism. A pawl 13 is carried by the gear 11 and is held by 75 a spring 14 in engagement with a ratchet 15 fixed on the inner end of the shaft 10. The pawl is arranged to drive the ratchet and shaft through the rotation of the gear 11 in one direction. Formed on the ratchet 80 15, is a hub 16 having a slot or recess 17 adapted to receive a catch 18, for locking the shaft 10 against rotation. The catch 18 is in the form of a lever pivotally mounted on the clamping part 9 of the bracket. 90

The driving mechanism is in the form of a bar 19, vertically slidable in the tubular standard 5, and having a rack 20 arranged to coact with the gear 11. Secured to the upper end of the rack bar, is a rod 21 which 95 extends through an aperture in the threaded cap 6. Bearing between the cap 6 and a disk 22 secured to the upper end of the bar 19, is a compression spring 23, which normally urges the rack bar to its lowermost position. A handle in the form of a head 24 is secured to the upper end of the rod 21 for raising the rack to its retracted position against the action of the spring 23. 100

The rotatable member 3 comprises a rod 105 25 having a hub 26 which is detachably secured to the shaft 10 by a tapered pin connection (not shown). Carried on one end

- of the rod, is an adjustable counter-weight 28 for balancing the weight of the flask 4, which is detachably secured at the other end of the supporting rod. The position of the counter-weight on the rod 25 may be adjusted by a thumb screw 29 which is threaded to the rod. The part of the rod which supports the flask 4 is bent at an angle which will permit the molten metal to flow into the matrix under the action of inertia as well as centrifugal force, as hereinafter described. The flask is detachably mounted between a fixed clamping member 30 and an adjustable clamping member 31, carried by the rod 25. The member 31 is adjustable along the bent part of rod 25 to accommodate different sizes of flasks and has a spring pressed bolt 32 for engaging a recess 33 in the opposed end of the flask.
- 20 The flask 4 is in the form of a metal shell having an open end 35 through which the plastic material is inserted for forming the mold. Part of the flask is cut away to form a seat 36 for a removable section or member 37, which comprises a pair of hinged parts 38 and 39 arranged so as to permit the blunt nose 40 of the part 39 to be inserted into the flask below the top member 41. The rear end of the part 38 is formed to provide an upright flange 42, which forms a finger grip to facilitate the insertion and removal of the member 37. Extending into the blunt nose 40, is an aperture 43 for receiving a sprue 44 which is arranged to support a wax or other fusible pattern (not shown) for forming the matrix in the mold. Several apertures may be formed in the nose 40 for receiving a plurality of sprues for the purpose of forming several matrices within the same mold. The bottom of the removable member 37 is formed to provide a pattern 45 for molding a crucible which communicates with the matrix through a channel which is formed in the mold by the projecting shank of the sprue 44, as hereinafter described.
- 46 In the operation of casting a dental inlay, a wax pattern or impression of the inlay is made and placed on the end of the sprue 44 which is then inserted into the aperture 43. The flask is removed from the machine and the section 37 is placed in the seat 36. A suitable plaster is then pressed through the open end 35 until the entire flask is filled and it is then allowed to set. When the plaster has hardened, the section 37 is removed from the flask, leaving the sprue imbedded in the mold. The sprue is then removed by a pair of pliers and the mold is heated to melt the wax pattern which is thereby absorbed by the material of the mold. If desired, the wax pattern may be washed out of the matrix by boiling water injected through the channel formed by the sprue. The flask is clamped in the machine

and the supporting arm 25 is secured against rotation by the catch 18 which engages the slot 17. In this position of the flask, the matrix is slightly higher than the crucible so as to prevent the molten metal from flowing out through the channel formed by the sprue. The gold or other metal is placed in the crucible and heated by a blow-torch or the like. When the metal in the crucible has all been melted, the rack bar is raised to its retracted position and the catch 18 is then released. The release of the catch permits the rack bar to move downwardly under the action of its spring, thereby rotating the gear 11 and shaft 10. When the rack bar reaches its lowermost position, the supporting rod 25 continues to rotate by its own momentum and the molten metal is forced outwardly from the crucible into the matrix where it hardens into the finished casting. The arrangement of the flask with respect to the rotatable support permits the metal to be acted upon by inertia as well as by centrifugal force. When the supporting member 25 stops rotating, the flask may be taken out of the machine and the cast removed by breaking the mold.

Although but one specific embodiment of this invention has been herein shown and described, it will be understood that numerous details of the construction shown may be altered or omitted without departing from the spirit of this invention as defined by the following claims.

I claim:

1. A device of the class described comprising a flask adapted for support on a centrifugal casting machine, said flask having a removable section comprising a pair of hinged parts, a pattern integrally formed on said removable section for molding a crucible, and a sprue mounted on one of said hinged parts for supporting a fusible pattern adapted to mold a matrix, said sprue being arranged to mold a channel providing communication between the matrix and crucible.

2. A device of the class described comprising a flask adapted for support on a centrifugal casting machine, and having an opening at one end, said flask having a removable section comprising a pair of hinged parts, a pattern integrally formed on said removable section for molding a crucible, and a removable sprue mounted on one of said hinged parts for supporting a fusible pattern adapted to mold a matrix, said sprue being arranged to mold a channel providing communication between the matrix and crucible.

Signed at Chicago this 27th day of Sept., 1921.

JAMES J. MOUNT.
